United States Patent Office.

EBERHARD FLUES, OF FORT WASHINGTON, (WHITEMARSH POST OFFICE,) PENNSYLVANIA.

Design No. 4,828, dated April 18, 1871.

DESIGN FOR A TALMA OR CLOAK GARMENT.

The Schedule referred to in these Letters Patent and making part of the same.

To all whom it may concern:

Be it known that I, EBERHARD FLUES, of Fort Washington, (Whitemarsh post office,) in the county of Montgomery and State of Pennsylvania, have invented and produced a Design for a Talma or Cloak Garment, which I term "*L'Espagnole*," and of which the following is a description.

In the accompanying drawing—

Figure 1 is a front view of a garment made according to my design, and

Figure 2 represents the shape of a portion of the same.

The garment is composed of an outer part, A, of the form of a cape or talma, to the interior of which

is attached a skeleton vest made of two pieces, of the shape shown in fig. 2, the upper edges *a* of which are attached to the outer part A at the shoulder, and the band-like portion *b* is attached by its extremity to the center of the back of the outer part A.

What I claim as my invention, and desire to secure by Letters Patent, is—

The design for a talma or cloak garment substantially as described, and as shown in the accompanying drawing.

EBERHARD FLUES.
